UNITED STATES PATENT OFFICE.

FREDERICK KOHNLE, OF DAYTON, OHIO, ASSIGNOR TO THE MONARCH MARKING SYSTEM COMPANY, OF DAYTON, OHIO, A CORPORATION OF OHIO.

PRICE TAG.

Application filed March 10, 1922. Serial No. 542,759.

To all whom it may concern:

Be it known that I, FREDERICK KOHNLE, a citizen of the United States, and residing at Dayton, in the county of Montgomery and State of Ohio, have invented a new and useful Price Tag, of which the following specification is a full disclosure.

This invention relates to improvements in price marking pin tags and pertains particularly to the construction of a double prong or pin wire clip, or fastener, fixed to the tag, as a means of securing the tag to the goods to be ticketed, and further pertains to the provision of a smooth dull pointed pin for the clip.

An object of the invention is to provide a wire pin clip as a tag fastener, with a base portion consisting of several bends, a single length of wire being looped and threaded through the tag material to provide a plurality of strand portions, clinched respectively against opposite sides of the tag and extending longitudinally of the width of the tag, furnishing a means for securely mounting the clip to the tag, and for sustaining the pin portion in an outstanding position with respect to the tag surface or plane, the free ends of the wire being respectively interposed and guarded between pairs of strand portions or bends at the reverse side of the tag, to prevent possible engagement of said ends with the goods to which the tag is applied, and to further prevent injury to the hands of the user.

The features of the invention will be more fully set forth in the description of the accompanying drawings forming a part of this specification, and in the drawings like characters of reference denote corresponding parts throughout the several views, of which:

Figure 1 is a plan view of a portion of gang tag strip, face side up, showing two full tags, each having one of my improved wire pin clips or fasteners at its upper margin.

Figure 2 is a plan view of the reverse side of the tag.

Figure 3 is a section on line 3, 3, Fig. 1.

Figure 4 is a section on line 4, 4, Fig. 3.

Figure 5 is a detached perspective view of my improved wire pin clip or fastener, with its elements disposed, as when fastened to the tag.

Price marking tags of the character here-

in disclosed are preferably formed in strips or gangs comprising a number of tags, said strips designed to be fed through a marking machine for printing the marking date upon the tags consecutively or successively and for severing the tags after being so marked, individually from the strip. The marking machines also are designed for applying the tags upon the goods to be ticketed, forcing the pins of the clip through the goods and clinching the same thereagainst. In order to non-interferingly feed the tags through the machine and maintain the pins in a position to be operated upon by the clinching mechanism thereof, it is desirable that the clip be securely mounted upon the tag with its pins in an outstanding position perpendicular to the plane of the tag, and in a double strand pin form of clip, to have the free or terminal ends of the wire of which the clip is formed protected and guarded.

Referring to Figs. 1 to 5 inclusive, 1 indicates a portion of a gang tag strip having a series of notches 2 cut inwardly from its upper longitudinal edge and definitely spaced apart for defining the tag widths. These notches in the strip provide shoulders for cooperation with the feeding mechanism of the marking machine for a step and measured feed advance of the strip. The pin clips, each as a fastener for the tag, are disposed in alignment at the upper margin of the tags respectively between the notches, each clip being formed of a single length of wire and bent to provide a base portion threaded through and clinched upon the tag material and a pair of outstanding double strand pins each presenting a rounded or dull point end.

The clip made from a single length of wire may be described as consisting of a pair of double strand pins each having its own base portion of a plurality of bends, engaging relatively upon opposite sides of the tag material with the bases joined together by a connecting bar or strand 3 as the intermediate portion of the wire length required in forming the clip. This connecting bar or strand 3 extends longitudinally of the width of the tag and preferably lies upon the face side thereof. At the opposite ends of the bar 3, the wire is bent to form return loops 4, 4, which thread through the tag material. From the loops, the wire ex-

tends substantially parallel with the bar 3 to provide base strands or bends 5, 5, respectively for the pins. These strands 5, 5, relatively extend in a direction toward each 5 other for a determined length, bearing against the reverse side of the tag material, and each forming a portion of the base of a respective pin. As the clip from such 10 opposite portion follows in duplicate for forming a pair of pins and their bases, the description will be confined to the singular.

From the inner end of the base strand or bend 5, the wire bends at an angle, thence by a return bend upon itself to form a 15 double strand pin 6, having a rounded point end 7. From the base of the return pin strand, the wire bends at an angle to provide a base strand 8 longitudinally adjacent its companion strand 5 on the reverse side 20 of the tag material. This strand 8 extends outwardly and lies opposite the corresponding end of the connecting strand 3, from which point the wire is bent into a loop 9 threaded through the tag, thence extends in- 25 wardly on the face side of the tag aside and parallel with the strand portion 3 for a determined distance and thence again loops and passes through the tag material at 11, to bring the free end 12 of the wire on the 30 reverse or pin projecting side of the tag. The free end 12 is clinched upon the tag reverse side between the base strands 5, 8, as shown in Figs. 2 and 4. This formation of 35 clip offers a base for each pin composed of a plurality of strands or bends clinched upon opposite sides of the tag in intimate engagement therewith, substantially anchoring the pins to the tag, giving increased 40 rigidity and stability to the pins, sustaining them in an outstanding or perpendicular position, and providing means for more positively securing the clip to the tag material. The clip can be made from a smaller gauge wire and the tag of a thinner weight 45 stock, affording a reduction in the cost of

material. Increasing the number of bases and clinching the same against one or both sides of the tag provides an increased bearing surface for the clip upon the tag, lessens the possibility of the clip cutting through the tag material when pulling the clip from the goods, increases the stability of the pin, and positively sustains the same in its upright or outstanding position.

Having described my invention, I claim: 55

1. A wire clip as a tag fastener, comprising a single length of wire bent to form an intermediate connecting bar, a plurality of back and forth bends at the opposite ends of said bar, adapted to provide loops for 60 threading through the tag material and pairs of parallel strands for clinching the tag material therebetween, and double strand pins leading at an angle from said bends at the opposite ends of said bar; the 65 free ends of the wire clinched upon one side of the tag material, each end between respective pairs of strands upon the corresponding side of tag material.

2. A wire clip comprising a single length 70 of wire formed to provide an intermediate connecting bar, back and forth bends at the opposite ends of said bar, providing relative opposite sets of reinforcing strands parallel with said bar, double strand fold 75 end pins respectively projecting at an angle from each set of strands and continuous therewith, and compressed together forward and return angle bends, providing rounded dull point pin ends, the free ends of the 80 wire extending parallel with said first named bends and respectively interposed between a pair thereof.

In witness whereof, I hereunto subscribe my name, as attested by the two subscribing 85 witnesses.

FREDERICK KOHNLE.
